UNITED STATES PATENT OFFICE.

ROSWELL E. MORELAND, OF TRENTON, NEW JERSEY.

WATCH-WINDING MECHANISM.

SPECIFICATION forming part of Letters Patent No. 451,566, dated May 5, 1891.

Application filed June 5, 1890. Serial No. 354,348. (No model.)

To all whom it may concern:

Be it known that I, ROSWELL E. MORELAND, a citizen of the United States, residing at Trenton, in the county of Mercer and State of New Jersey, have invented certain new and useful Improvements in Watches, of which the following is a specification.

My invention relates to the attachment of the ratchet-wheel to its bearings; and its object is to provide means of attaching and confining the ratchet-wheel to its bearings in such manner as to obviate the present unsatisfactory means for securing the same in its place and to retain the wheel on its bearings while the movement is being repaired and is but partially assembled, thus saving the person manipulating the movement trouble and care.

I shall now describe my said invention with reference to the drawings, in which—

Figure 1 is a plan view of the front of the pillar-plate of a watch-movement; Fig. 2, a plan view of the back of said plate; Fig. 3, a plan view of the back of said plate with the ratchet-wheel attached thereto in my improved manner; Fig. 4, a front view of said plate, showing my means of attaching the ratchet-wheel; Fig. 5, a plan view of the back of a ratchet-wheel; Fig. 6, a side view of the ratchet-wheel with the arbor attached thereto; Fig. 7, the collet or band for attaching the wheel to the plate; and Fig. 8, the barrel-arbor, the barrel being removed.

Heretofore the usual means of holding the ratchet-wheel in place has been a bridge projecting over the plate which served to hold the wheel against the plate, and unless the plate was countersunk to hold the wheel the wheel would slip out of place in horizontal plane as soon as the barrel and barrel-arbor were removed from their places. Even when the plate was countersunk the ratchet-wheel necessarily had some lateral motion when the barrel-arbor was removed, and it required readjustment preparatory to reassembling the movement, a matter of considerable inconvenience.

My improvement consists in providing the ratchet-wheel with an arbor which is passed through the pillar-plate, and in attaching to

the outer end of the arbor a collet or band. The ratchet-wheel being on one side of the pillar-plate and the collet on the other side, the wheel is held exactly in its place. The ratchet-wheel arbor is provided throughout 55 its length, or a part thereof, with a rectangular recess into which the barrel-arbor fits snugly, thus causing the barrel to turn with the ratchet.

In assembling a watch-movement containing my improvement the ratchet-wheel arbor is passed through the hole in the pillar-plate (shown at *b* in Fig. 2) and the ratchet-wheel is brought into position, as shown in Fig. 3. The collet *c* is then sprung, screwed, or riveted 60 on the ratchet-wheel arbor, fitting snugly against the shoulder shown on the arbor in Fig. 6. The square end *d* of the barrel-arbor is then inserted in the rectangular opening 65 in the ratchet-wheel arbor (shown at *e* in Fig. 70 4) and the barrel is passed to its place and the adjustment is complete.

It will be obvious that in using my improved device it is unnecessary to countersink the pillar-plate for the ratchet-wheel, 75 and that the ratchet-wheel may be placed on either side of the plate by making the ratchet-wheel arbor hollow throughout its entire length to receive at either end the rectangular end of the barrel-arbor. It will also be 80 apparent that my device may be used with equal advantage in attaching the ratchet-wheel to the top plate when it is desired to use that plate for the purpose. Again, it will be seen that the details of my device may be 85 somewhat varied without departing from my invention. For instance, the ratchet-wheel arbor may be made solid and the barrel-arbor hollowed to receive the same, and with such construction instead of the collet or band a 90 pin or similar fastening in the ratchet-wheel arbor may be used; but I have shown herein what I consider to be the best manner of applying my improvement.

What I claim as new, and desire to secure 95 by Letters Patent, is—

1. In a watch-movement, a ratchet-wheel, a stub-arbor carrying the ratchet-wheel only, said stub-arbor engaging with the mainspring-arbor; and a fastening device for detachably 100

securing the stub-arbor in the plate, substantially as described.

2. In a watch-movement, the combination, with the plate, of a ratchet-wheel, a stub-arbor supporting said wheel in the plate and engaging with a separate arbor for the main-spring on the other side of the plate, and a

fastening device on the same side of the plate as the mainspring for securing the stub-arbor in the plate, substantially as described. 10
